US0D1098038S

(12) **United States Design Patent** (10) **Patent No.:** **US D1,098,038 S**
(45) **Date of Patent:** **** Oct. 14, 2025**

(54) **PLUG SOCKET**

(71) Applicant: **Yuyao Yunjin Electrical Appliance Co., Ltd, Zhejiang (CN)**

(72) Inventor: **Jun Li, Zhejiang (CN)**

(**) Term: **15 Years**

(21) Appl. No.: **29/920,819**

(22) Filed: **Dec. 13, 2023**

(51) **LOC (15) Cl. 13-03**

(52) **U.S. Cl.**

USPC **D13/137.4**

(57) **CLAIM**

The ornamental design for a plug socket, as shown and described.

DESCRIPTION

FIG. 1 is a first perspective view of a plug socket showing my new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof; and,

FIG. 8 is a second perspective view thereof.

1 Claim, 8 Drawing Sheets
